UNITED STATES PATENT OFFICE.

ISRAEL LUDLOW, OF NEW YORK, N. Y.

SUBMARINE-TRAP.

1,249,144.

Specification of Letters Patent.

Patented Dec. 4, 1917.

Application filed June 18, 1917. Serial No. 175,341.

To all whom it may concern:

Be it known that I, ISRAEL LUDLOW, a citizen of the United States, and a resident of the city of New York, borough of Manhattan, in the county and State of New York, have invented a new and Improved Submarine-Trap, of which the following is a full, clear, and exact description.

Among the principal objects which the present invention has in view are: to sink a submarine to depths where the static pressure is greater than the resistance of the submarine hull; to destroy a submarine by changing the riding angle thereof; to entangle a submarine and prevent the disengagement thereof prior to inflicting damage thereon; to recover the traps if the same become released accidentally; to optically locate an invisible submarine; and to simplify the construction of the trap employed for carrying the above-stated objects into effect.

Drawings.

Figure 1 is a perspective view of a portion of a trap and supports therefor constructed and arranged in accordance with the present invention;

Fig. 2 is a vertical section of a weight and supporting buoy therefor constructed and arranged in accordance with the present invention;

Fig. 3 is a perspective view of a weight and buoy support therefor constructed and arranged in accordance with a modified form of the invention;

Fig. 4 is a longitudinal section of a buoy for supporting a weight and net attached thereto, said buoy being constructed and arranged in accordance with a modified form of the invention;

Fig. 5 is an end view of the same.

Description.

As seen in the drawings, a net 10 of any desired length and width is suspended at intervals by short supporting lines 11. The lines 11 are connected with heavy weights 12. In the form of the invention disclosed

in Figs. 1 and 2 of the drawings, each line 11 is directly connected with an eye-bolt 13. The eye-bolt 13 is bored to provide a housing for a suspending rod 14. Each rod 14 has a hook 15, which extends through a slot

16 to rest on a slit center plate 17. The rod

14 has provided thereon a spiral flange 18, which engages a suitable slot section in the tubular extension 19 of the bolt 13.

The weight carried by each of the lines 11 is supported by a spring 20. The spring 20 permits a lengthwise movement of the rod 13 independent of the rod 14. The engagement between the rod 14 and the tubular extension 19 operates to turn the rod 14 whenever the rod 13 is depressed sufficiently to accomplish this purpose. The engagement referred to embodies a pin 21, the flange 18, pin 22 and guide slot 23. The slot 23 engages the pin 22 to prevent rotation of the rod 13. When the pin 21 descends on the flange 18, the said flange is displaced to rotate the rod 14. This rotation of the rod continues until the hook 15 alines with the slot 16, when the weight 12 being unsupported sinks through the water carrying the net 10 with it.

It is evident that the weights 12 and parts associated therewith are directly carried by the rods 14, and hooks 15 associated with each of the weights. The plates 17 with which the various hooks 15 are engaged are centrally disposed in a spider frame. The frame 24 provides out-riggers 25, at the terminals whereof sea anchors 26 of frusto-conical shape are carried. In the form of the invention disclosed in Figs. 1 and 2 of the drawings, said spider frame and anchors are supported on buoys 27. The buoys 27 in this form of the invention are preferably circular in form, providing a hollow central opening wherein the weight 12 is housed.

In Fig. 3 of the drawings, a modified form of the invention is disclosed. The modification consists in providing a square or platform buoy 28, whereon a weighted member 29 is supported. The member 29 is held on the platform 28 by a guide rail 30. The rail 30 may have undercut side edges, as shown in said figure, or may be rectangular. The weighted member 29 is provided with supporting arms 31. The arms 31 have eyelets at the extremities thereof to which are secured the lines 32, whereby is supported the net 10.

A further modification in this form of the invention consists in connecting the sea anchors 26, with which it is provided, by means of the spider arms 33, one of which is preferably secured to each corner of the float or buoy 28.

In Figs. 4 and 5, a further modification of the structure is disclosed. The modification herein shown consists principally in that the float or buoy provides two pontoons 34 disposed in paired and parallel relation. A frame 35 maintains the space relation of the pontoons 34. Between the pontoons extends a platform 36. Extending upward from the platform 36, are standards 37, 10 which provide bearings for a line-reel, or winch 38. The line 39 with which said reel is provided, is directly secured to a weight 40, employing for this purpose, an eyelet 41. From the under side of the platform 36 extend bearing lugs 42, through which a dowel pin 43 extends. The pin 43 passes through the head of an arm 44 integrally formed with the weight 40. A suitable nick is provided in the pin 43 to receive 20 a spring latch 45. The latch 45 serves to normally maintain the pin 43 within the bearings of the lugs 42 and the arm 44. The end of the pin 43 is directly connected with the line 46, which supports the net 10. In 25 this form of the invention, it will be noted that the line 11, which is directly connected with the weight, is normally slackened. It is the line 11 which directly connects the weight 40 and net 10 to carry the latter down 30 when the weight is permitted to plunge.

Operation.

In all of the forms of the invention, it will be noted that the weights carried by 35 the floats are permitted to plunge or sink through the water in which the floats are placed when a pull greater than the weight of the net is exerted on the latches or other devices by which the weights are suspended 40 from the floats. This happens only when a submarine encounters the net 10 and presses the same forward, exerting a drag on the various floats, which is resisted by the sea anchors 26 connected therewith. It 45 will be noted that when this pulling pressure is exerted upon the net and the supporting lines therefor, the net will be extended forward of the various floats, and that the weights carried by the said floats 50 will be buoyed well to the rear of the submarine. In this position, the latches are released by the pull above referred to, and the weights are permitted to plunge downward through the water. The combined 55 weights supporting the net are sufficient to overcome the buoyancy of the submarine, and operate to sink the same, wrapping the structure in the folds of the net.

The strain exerted on the net and by the 60 net on the submarine, is such as to prevent the exit therefrom of a diver for clearing the submarine of its entanglement in the net.

Further, it will be observed that the pull of the combined weights on the submarine 65 and net would be such as to up-point the

submarine, the major portion of the weight being well aft of the center of buoyancy of the submarine. The up-ending of the submarine in this manner has a disastrous effect on the structure and cargo or ballast 70 carried thereby.

If the water in which the submarine is trapped be deep enough to carry it below that where the static pressure of the water is greater than the pressure of the air within the hull, the result would be that the hull of the submarine would be crushed by the external pressure.

Claims.

1. A submarine trap comprising a net-like member; a plurality of weights operatively attached to said member; a plurality of buoys for supporting said weights and member; and means operable through the medium of said member for detaching said weights from said buoys.

2. A submarine trap comprising a net-like member; a plurality of weights operatively attached to said member; a plurality of buoys for supporting said weights and member; and means operable through the medium of said member for detaching said weights from said buoys, said means embodying a latch pin, and connections uniting the same and said member, said connections being so arranged that the displacement of said member operates to pull said latch pin.

3. A submarine trap comprising a net-like member; a plurality of sinking weights mounted on said member; means for floating said member and weights under normal conditions; and means for suspending the flotation of said weights and member.

4. A submarine trap comprising a net-like member submersible in the path of a submarine; means imparting to said member a weight sufficient to sink the submarine; and means for floating said net-like member, the flotation of said means being destructive when said member is engaged by the submarine.

5. A submarine trap comprising a net-like member submersible in the path of a submarine; weights connected with the upper edge of said member, said weights being adapted to overload the flotation of the submarine; means for floating said weights and net-like member connected therewith; and means for releasing said member and weights and permitting the latter to sink when the member is engaged by a submarine, to be carried beyond the vertical plane in which said weights are disposed.

6. A submarine trap comprising a net-like member submersible in the path of a submarine; weights connected with the upper edge of said member, said weights being adapted to overload the flotation of the

submarine; means for floating said weights and member connected therewith; means for releasing said member and weights and permitting the latter to sink when the member is engaged by a submarine, to be carried beyond the vertical plane in which said weights are disposed; and means connected with said weights for restraining the movement thereof through a floating medium.

7. A submarine trap comprising a net-like member submersible in the path of a submarine; weights connected with the upper edge of said member, said weights being adapted to overload the flotation of the submarine; means for floating said weights and member connected therewith; means for releasing said member and weights and permitting the latter to sink when the member is engaged by a submarine, to be carried beyond the vertical plane in which said weights are disposed; and means connected

with said weights for restraining the movement thereof through a floating medium, said means embodying sea anchors temporarily attached to said weights to be released therefrom when necessary strain is imparted to the net and weights attached thereto.

8. A submarine trap comprising a submersible net; a plurality of plunging weights operatively connected with said net at the upper edge thereof; a plurality of flotation buoys, each operatively connected to support one of said weights; a releasable latch operatively connecting each of said weights and its respective buoy; means operatively connecting said latch and said net, whereby the horizontal displacement of said net relative to said buoys releases said latch; and sea anchors, one connected with each of said buoys for restraining the lateral movement thereof.

ISRAEL LUDLOW.
